TOY TRUCK CAB

Jorma Vennola, Princeton, and Erkki Pekka Korpilaakko,
Heightstown, N.J., assignors to Columbia Broadcasting
Systems, Inc.

Filed July 12, 1972, Ser. No. 270,928

Term of patent 14 years

Int. Cl. D21—01

U.S. Cl. D34—15 AJ

FIG. 1

FIG. 2

FIG. 3

FIG. 4

FIG. 1 is a top plan view of a toy truck cab showing our new design;

FIG. 2 is a front perspective view thereof;

FIG. 3 is a front elevational view thereof;

FIG. 4 is a side elevational view thereof.

We claim:

The ornamental design for a toy truck cab, substantially as shown.
